(57) **CLAIM**

The ornamental design for a three-way clip for holding catheter hose, as shown and described.

DESCRIPTION

FIG. 1 is a front perspective view of a three-way clip for holding catheter hose showing our new design;

FIG. 2 is a side elevational view thereof;

FIG. 3 is an opposite side elevational view thereof;

FIG. 4 is a front elevational view thereof;

FIG. 5 is a rear elevational view thereof;

FIG. 6 is a top plan view thereof; and,

FIG. 7 is a bottom plan view thereof.
